UNITED STATES PATENT OFFICE

JOHN W. HARMON, OF CANTON, OHIO, ASSIGNOR TO THE GILLIAM MANUFACTURING COMPANY, OF SAME PLACE.

DESIGN FOR A COACH-PAD.

SPECIFICATION forming part of Design No. 30,273, dated February 28, 1899.

Application filed February 4, 1899. Serial No. 704,585. Term of patent 14 years.

To all whom it may concern:

Be it known that I, JOHN W. HARMON, a citizen of the United States, residing at Canton, Stark county, Ohio, have invented and 5 produced a new and original Design for Coach-Pads, of which the following is a specification, reference being had to the accompanying drawings, forming a part thereof.

Figure 1 is a rear elevation of a coach-pad, 10 showing my new design. Fig. 2 is a sectional perspective view taken on the line 22 of Fig. 1.

Coach-pads as commonly constructed consist of a curved flanged metal pad-plate, a leather-covered pad secured to the underside 15 of the plate, and a leather strap secured upon the plate between the flanges thereof. It is to a coach-pad having this general construction that my invention relates.

As shown in the drawings, the leading or 20 material features of my design consist in extending the edges of the pad a short distance in front of and behind the pad-plate, to the under side of which the pad is secured, and in securing two beaded strips between the plate 25 and pad, the beads whereof lie upon and pro-

ject partly across the top surfaces of the projecting edges of the pad. In other words, a pad embodying my design has a curved pad-plate A and a leather-covered pad B, lying against the under side of said plate and having its edges *b b* projected both forwardly and rearwardly beyond the corresponding edges of the plate and having upon the top surfaces of the projecting edges of said pad and close to the edges of the pad-plate the beads C C. 30 35

It is manifest that the beads C C may, if desired, be of a different color from the other parts of the pad.

Having described my invention, what I claim as new, and desire to secure by Letters 40 Patent, is—

The design for a coach-pad as herein shown and described.

In testimony whereof I hereunto affix my signature in the presence of two witnesses. 45

JOHN W. HARMON.
